(57) **CLAIM**

The ornamental design for a patella clamp, as shown and described.

DESCRIPTION

FIG. 1 is a front perspective view of a design of one embodiment of the patella clamp;

FIG. 2 is a first side elevation view of the patella clamp of FIG. 1, the second side elevation view of the patella clamp being a mirror image of the first side elevation view shown in FIG. 2;

FIG. 3 is a rear elevation view of the patella clamp of FIG. 1;

FIG. 4 is a front elevation view of the patella clamp of FIG. 1;

FIG. 5 is a top plan view of the patella clamp of FIG. 1;
FIG. 6 is a bottom plan view of the patella clamp of FIG. 1;
FIG. 7 is a rear perspective view of the patella clamp of FIG. 1;

FIG. 8 is a front perspective view of a design of another embodiment of the patella clamp;

FIG. 9 is a first side elevation view of the patella clamp of FIG. 8, the second side elevation view of the patella clamp being a mirror image of the first side elevation view shown in FIG. 9;

FIG. 10 is a rear elevation view of the patella clamp of FIG. 8;

FIG. 11 is a front elevation view of the patella clamp of FIG. 8;

FIG. 12 is a top plan view of the patella clamp of FIG. 8;
FIG. 13 is a bottom plan view of the patella clamp of FIG. 8; and,

FIG. 14 is a rear perspective view of the patella clamp of FIG. 8.
